Attorney.

UNITED STATES PATENT OFFICE.

CHARLES B. BAUMGARTNER, OF MANCHESTER, IOWA.

FENCEPOST.

1,343,544.

Specification of Letters Patent. Patented June 15, 1920.

Original application filed May 20, 1919, Serial No. 298,454. Divided and this application filed September 8, 1919. Serial No. 322,490.

To all whom it may concern:

Be it known that I, CHARLES B. BAUMGARTNER, a citizen of the United States of America, and a resident of Manchester, 5 Delaware county, Iowa, have invented certain new and useful Improvements in Fenceposts, of which the following is a specification.

My invention relates to improvements in 10 fence posts, and the object of my improvement is to construct a metal fence post with integral fastening means for fence wires, which will permit the wires to be easily and quickly connected to the post and be firmly 15 and securely held thereon.

This application is a division of my pending application, Serial No. 298,454, filed May 20, 1919.

The above object has been successfully 20 accomplished by the means which are herein-after described and claimed, and which are illustrated in the accompanying drawings, in which Figures 1 and 2 are elevations of 25 my improved fence post, taken at an angle of ninety degrees from each other; Fig. 3 is an enlarged detail elevation of the upper end of the post showing the method of securing a fence wire thereon, and Fig. 4 is an enlarged cross section of said post taken 30 above the anchoring device thereon.

Similar numerals of reference denote corresponding parts throughout the several views.

The metal post 1 may be of any desired 35 form of cross section, but is preferably made of T-bar section with the usual medial web or flange 2. Upon the lower part of the post and spaced some distance from its lower end, a special anchoring device is fixed 40 being a plate bent and shaped to provide two hollow structures 9 and 10 secured to the main body of the post by rivets, and to the web 2 by bolts 6. This device, when embedded in the ground as shown in Figs. 45 1 and 2, serves to firmly anchor the post against different lateral strains, but this device will not be more particularly described herein, as it forms the subject matter of my said co-pending application.

50 My improved wire fastening means are produced by suitable section and slotting of the web 2. The operation may be performed by any desired means, but results in the making of a number of spaced rec-

tangular longitudinally alined slots or ori- 55 fices 5 and the partial cutting away of tongue-shaped projections 3 along said ori- fices. The projections 3 are bent to one side to extend upwardly and obliquely, with their upper ends sufficiently far from the 60 web 2 to permit of the insertion therebe- tween of a fence wire 7.

The method of mounting the wire 7 in the above described fastening means is shown in Fig. 3. The wire 7 is grasped 65 between the hands and obliquely bent so that it may be passed through the inter- space of the projection 3 and the web 2 to enter the upper part of the slot 5, where it normally, when under longitudinal strain, 70 rests in contact with the upper horizontal wall 4 of the slot. This wall forms a shoul- der that retains the wire, and as the shoul- der 4 is located intermediate the length of 75 the projection 3, the wire cannot escape from said slot unless it is manually removed by reversing the action illustrated in Fig. 3. It is therefore not necessary to close the projections 3 after the wires are so inserted 80 in the slots as the wires are sufficiently se- cured and may be readily removed when desired.

Having described my invention, what I 85 claim as new and desire to secure by Letters Patent, is:

1. A post having wire receiving and holding means, said means consisting of a pro- 90 jection partially incised from the post rec- tangularly and bent at a small angle there- from opening upwardly, the incision re- moving a portion of the post to provide a slotted orifice with the top of the slot con- 95 stituting a shoulder located below the top of the projection.

2. A post having a vertical longitudinal 95 rib, said rib having a rectangular longi- tudinally elongated slot, the rib being slit longitudinally upward beginning from the upper outer corner of the slot, then out- 100 wardly horizontally to its outer edge, pro- viding an upwardly projecting tongue off- set at its upper part above the level of said slot, said tongue being bent laterally slightly to afford clearance for reception of an obliquely disposed wire into the slot. 105

Signed at Waterloo, Iowa, this 6th day of August, 1919.

CHARLES B. BAUMGARTNER.
